SPHYGMOMANOMETER DIAL FACE

Merton J. Alexander, 173 Highland Place,
Monrovia, Calif. 91016

Filed Dec. 6, 1974, Ser. No. 530,204

Term of patent 14 years

Int. Cl. D24—02

U.S. Cl. D83—1 F

Fig. 1.

Fig. 2.

FIG. 1 is a perspective view of a sphygmomanometer dial face showing my new design; and

FIG. 2 is a perspective view of a modification of the design of FIG. 1.

The respective sides not shown are plain.

I claim:

The ornamental design for sphygmomanometer dial face, as shown and described.
